X-RAY APPARATUS

Oscar H. Pieper, Rochester, N. Y.

Application May 11, 1928. Serial No. 276,882

15 Claims. (Cl. 250—34)

My invention relates to X-ray apparatus and contemplates improvements to the end of safety in handling while in operation.

In order to accomplish this purpose, the desideratum is a metallic container for the tube, but the problems of high voltage isolation and of the necessary manipulation of the tube must be met before protection by such means can be realized.

10 I provide a metallic container, and ground it, and, in order to keep it within practical dimensions, I give it a spherical form in proximity to the high tension terminal of the X-ray tube, which terminal, in turn, I surround with a concentric spherical housing, experiment having shown that between spherical surfaces lesser distances are feasible without discharge across the gap between them. And the structure of my invention provides appropriate insulation of the

20 high voltage circuit in all other respects as well.

My structure accommodates the standard tube and does so in such a way that, although the tube is enclosed, the usual cone, which identifies the center line of the ray, is capable of the same 25 range of adjustment as that which now obtains in the case of un-enclosed tubes, this being accomplished by the particular mechanical constructions and arrangements of parts which constitute features of my invention.

30 Moreover, as will appear, I give heed to simplicity and effectiveness of design and provide improved means of support and electric current supply, all to the ends of increased utility, practicability and safety to operator and patient.

35 My invention is illustrated in the accompanying drawings, in which,

Figure 1 is an elevational view of an X-ray structure embodying my invention, illustrating the means for supporting the assembly with 40 which my invention has to do, this view being supplemented by a diagrammatic showing of a typical circuit therefor;

Figure 2 is a cross sectional view, on a larger scale, taken on the plane of the line 2—2 of Figure 1 and looking in the direction indicated by the arrows; and

Figure 3 is a cross sectional view taken on the plane of the line 3—3 of Figure 2 and looking in the direction indicated by the arrows.

50 Referring first to Figure 1, the main supporting arm, which extends from the X-ray apparatus, is shown at 4, this main supporting arm having the auxiliary supporting arm 5 slidably mounted thereon. The downwardly extending forearm 6

55 is pivotally mounted upon the free end of the

auxiliary supporting arm 5, upon the axis x, a locking screw 7 being provided to hold the forearm in any adjusted position. The forearm 6 terminates in a supporting ring 7 in which a vertically adjustable supporting tube 8 is mounted, a thumb screw 9 being provided to set the tube 8 in any adjusted position. The lower end of the tube 8, below the ring 7, is forked into tubular branches 10 and 11 extending obliquely downwardly. A metallic container 12, shown in greater detail in Figures 2 and 3, is attached to the lower ends of the fork branches 10 and 11, the interior of these branches connecting with the interior of the container as clearly shown in Figure 3.

The container 12 is of tubular formation and is closed at one end by the hemi-spherical wall 13 and at its other end by a hemi-spherical cap 14.

55 In its middle portion, the container 12 is provided with an oblong slot 15 which extends part way around the container, as best shown in Figure 2, and which has its sides lying in planes at right angles to the axis of the container.

Within the container, rings 16 and 17, having 60 peripheral flanges, are mounted, as will appear presently, for angular movement, these rings being of insulating material and being for the purpose of supporting X-ray tube 18 co-axially with the container 12.

65 The X-ray tube 18 is of standard form, passing through the rings, as shown in Figure 3, the enlarged central portion thereof being clamped between them. The ring 16 is provided with pillars 19, 19 extending toward the ring 17, and 70 screws 20, 20, passing through the ring 17, thread into nuts anchored in the ends of these pillars.

75 By this means the two rings may be drawn together appropriately to clamp the enlarged middle portion of the X-ray tube between them, felt pads 21, 21 being provided between the X-ray tube and the rings for cushioning purposes. The respective rings are disposed at the sides of the slot 15, as shown in Figure 3, and their peripheries are embraced by a collar 22 which serves 80 to close the slot whatever may be the angular position of the rings within the range of action provided. This is clear from Figure 2.

85 The collar 22 is provided with a circular opening surrounded by a rim 23 which extends outwardly through the slot 15 upon an axis intersecting the axis of the X-ray tube and the container. An internally threaded supporting ring 24 fits into the rim 23 and is secured thereto by means of screws 25, 25. The usual X-ray

105

110

cone, of hard rubber, shown at 26, is screwed into the supporting ring 24, as best shown in Figure 2.

The collar 22 is held upon the rings 16 and 17 by means of screws 27, 27 threaded in nuts lodged in the rings, as indicated in Figure 3. Felt rings 29, 29 lie between the inner surface of the container 12 and the rings 16 and 17, engaging preferably in grooves 30, 30 in the peripheries of the rings, as shown. By this means the X-ray tube is further cushioned relative to the container 12 and the rings 16 and 17 are permitted to ride easily in their angular movement.

The cone 26 is positioned to identify the center line of the ray from the focal spot and is manipulated to direct the rays where desired. For instance, in dental work, it is usual for the operator to place the apex of the cone against or near the face of the patient, with its axis set in the desired direction of the rays for the purpose of producing a so-called radiograph upon the film held within the mouth of the patient. By reason of the adjustability of the parts 4, 5, 6 and 8, the container 12 can readily be brought to appropriate position, the ability of the tube 8 to move angularly about its own axis permitting the appropriate disposition of the axis of the container and therefore of the tube. The final adjustment, i. e., the adjustment of the cone, may then be made to any degree of nicety required. As shown in the drawings the axis of the cone has an adjustment through an angle of about 115 degrees, this being determined by the length of the slot 15 and being indicated by the dotted lines in Figure 2.

The filament end of the X-ray tube is provided with terminals 31, 31, which are connected in circuit by means of conductors 32, 32, leading through the tubular fork branch 11 and out through a convenient opening 33 provided at the yoke.

The high tension terminal 34 is provided with a radiator, as is usual in the art, the radiator in this instance, however, comprising fins of varying diameter, as shown in Figure 3, in order to approximate an over-all spherical contour. Thus formed, the radiator 35 is surrounded by a spherical metallic housing 36 disposed concentrically with the hemi-spherical end 13. The high tension conductor 36' enters the container 12 by way of the tubular support 8 and the tubular fork branch 10, being lodged in soft rubber tubing 37 passing through the tubular members 8 and 10. The lower end of the high tension conductor 36', which is of generous diameter, is provided with a socket 38 in which a spring pressed contact plunger 39 is disposed, this plunger, as shown in Figure 3, engaging with the surface of the sphere 36 as part of the high voltage circuit. It will now be clear that as the X-ray tube 18 is adjusted angularly, the plunger 39 will ride upon the outer surface of the sphere 36, making continuous contact therewith, in order to maintain the high voltage circuit whatever may be the adjustment of the X-ray tube.

The high voltage conductor 36' leads to the top of the tubular support 8 where, at 40, the high tension wire 41 is connected. This high tension wire, supported in insulators 42, 42, mounted upon the main supporting arm 4 and forearm 5, respectively, leads back to the transformer in the apparatus.

I have shown in Figure 1, a typical circuit, the elements of which are provided with suit-

able legends making further descriptive matter with reference thereto unnecessary. Under ordinary conditions, the high voltage will not jump across the gap between the sphere 36 and the end 13 of the container, even though they are as closely related as the proportions shown indicate, this being due, as before pointed out, to the spherical formation of the gap terminals. Moreover, in the event of an abnormal condition, a discharge across the gap would be harmless, since the high tension circuit is grounded and since the jump is to the container which is also grounded, thus having no tendency to go to a person touching the container. The container may therefore be readily handled while the tube is in operation.

I claim:

1. In X-ray apparatus, a supporting arm, a grounded metallic tubular container adjustably mounted on said arm and having a slot in the cylindrical wall thereof, a supporting structure movably mounted within said container and having a focusing member extending through said slot, an X-ray tube isolated in said container in said supporting structure, a filament circuit for said X-ray tube, and a high tension circuit for said X-ray tube, said high tension circuit being grounded.

2. In X-ray apparatus, a supporting arm, a grounded metallic tubular container adjustably mounted on said arm and having an opening in the cylindrical wall thereof, an X-ray tube rotatably mounted in said container, said container surrounding said X-ray tube apart from other apparatus, a focusing member mounted to rotate with said X-ray tube and extending through said opening for movement therein, a filament circuit for said X-ray tube, and a high tension circuit for said X-ray tube, said high tension circuit being grounded.

3. In an X-ray tube mounting, a tubular housing having a slot in the cylindrical wall thereof, an annular supporting structure, the outer periphery of said structure being concentric with and having bearing relation to the inner surface of said housing, and an X-ray tube having its midportion fitting in said supporting structure.

4. In an X-ray tube mounting, a tubular container having a slot in the cylindrical wall thereof, a pair of rings of insulating material mounted for rotary movement in said container, and an X-ray tube having the enlarged central portion thereof thereof clamped between said rings.

5. In an X-ray tube mounting, a tubular container having a slot in the cylindrical wall thereof, a pair of rings of insulating material mounted for rotary movement in said container, an X-ray tube having the enlarged central portion thereof clamped between said rings, and a cone mounted upon said rings and extending through said slot.

6. In an X-ray tube mounting, a tubular container having a slot in the cylindrical wall thereof, a pair of rings of insulating material disposed within said container, felt packing rings between said first-named rings and said cylindrical wall, whereby said first named rings may be moved angularly, and an X-ray tube having the enlarged central portion thereof clamped between said first named rings.

7. In an X-ray tube mounting, a tubular container having a slot in the cylindrical wall thereof, a pair of rings of insulating material mounted for rotary movement in said container, a collar embracing and secured to said rings and having a lateral supporting rim extending through said

- slot, and a cone mounted upon said supporting rim.
8. In combination, a tubular metallic container having a hemi-spherical end, an X-ray tube supported co-axially within said container and having a high voltage terminal radiator surrounded by a metallic housing with a spherical surface disposed concentrically within said hemi-spherical end.
- 10 9. In combination, a tubular metallic container having a hemi-spherical end, an X-ray tube supported co-axially within said container and having a high voltage terminal radiator surrounded by a metallic spherical housing disposed concentrically within said hemi-spherical end.
- 15 10. In combination, an X-ray tube having its high voltage terminal provided with a radiator comprising fins of varying diameter to present a spherical contour, a metallic spherical housing fitting over said radiator, a container enclosing said X-ray tube and having a hemi-spherical end disposed concentrically with and distanced from said spherical housing.
- 20 11. In combination, a tubular container having hemi-spherical ends and having a slot in the cylindrical wall thereof, a supporting structure mounted in said container for rotary movement therein, an X-ray tube mounted in said supporting structure co-axially with said container, and with its focal spot in the zone of said slot, the high voltage terminal of said X-ray tube being enclosed by a spherical housing disposed concentrically with one of said ends.
- 25 12. In combination, a metallic container with a hemi-spherical end, an X-ray tube rotatably supported in said container and having its high voltage terminal enclosed by a metallic housing
- 30 with a spherical surface in said hemi-spherical end, a conductor leading to said high voltage terminal, and wiping contact means between said conductor and said spherical surface.
- 35 13. In combination, a metallic container with a hemi-spherical end, an X-ray tube supported in said container and having its high voltage terminal enclosed by a spherical housing in said hemi-spherical end, said tube being capable of angular adjustment on its own axis, a high voltage conductor leading into said container and having wiping contact upon said spherical housing.
- 40 14. In combination, a metallic container with a hemi-spherical end, an X-ray tube supported in said container and having its high voltage terminal enclosed by a spherical housing in said hemi-spherical end, said tube being capable of angular adjustment on its own axis, a high voltage conductor leading into said container, and a spring pressed plunger for the end of said high voltage conductor engaging said spherical housing.
- 45 15. In combination, a tubular container mounted upon a tubular fork extending from a tubular support, an X-ray tube mounted for rotary movement within said container, a soft rubber hose disposed in one branch of said fork, a high tension wire passing through said tubular support and said hose to within said container where it is connected to the high voltage terminal of said X-ray tube, and conductors for the filament of said X-ray tube leading from terminals at the other end thereof through the other branch of said fork.
